Primary Examiner — Susan Moon Lee

CLAIM

The ornamental design for an imaging device, as shown and described.

DESCRIPTION

FIG. 1 is a front perspective view of an imaging device according to a an embodiment of our design;

FIG. 2 is a rear perspective view thereof;

FIG. 3 is a front elevational view thereof;

FIG. 4 is a right side elevational view thereof, the left side elevational view being a mirror image of the right side elevational view;

FIG. 5 is a back elevational view thereof; and,

FIG. 6 is top plan view thereof.

The bottom of the imaging device is not being claimed.
